signors to Chase Protected Cultivation Limited,
Chertsey, England

Application November 13, 1946, Serial No. 709,470
In Great Britain December 29, 1945

5 Claims. (Cl. 47—29)

1

This invention relates to cloches of the barn type, i. e., the type having two transparent plates (generally of glass) on at least one side of a handle forming a pressure member engaging an internal tension member over which the transparent plates are supported.

According to the present invention a support is provided adjacent to the uppermost plate of a pair on one side of the handle to enable that plate to be removed without disturbing the rigidity of the remainder of the structure, as may be desirable for ventilation, access to plants, or the admission of rain.

The support is preferably in the form of a frame having two parallel sides, the upper side adapted to clip under lateral projections of a handle pressure member and the lower side adapted to engage a member of the cloche structure disposed adjacent to the lower edge of a plate at one side of the handle.

The frame may be a closed panel, with its lower side formed with a loop for engagement with the internal tension member and turning at each end into pairs of serrations, the serrations of each pair being adapted to engage respectively the lower edge of an upper plate and the upper edge of a lower plate. The end members, which may be at right angles or somewhat inclined to the two parallel sides, space the sides apart by an amount approximating to the width of an upper plate, and thus permit that plate to be removed when desired.

If the cloche has only one internal tension member, the loop for engagement therewith in the lower side of the frame is preferably central; if two or more tension members are provided, the lower side of the frame loops round each.

The loop or loops for engagement with the tension member or members may form serrations adapted to engage the edge of at least one of the plates at that side of the cloche, and preferably of both of the plates.

The frame is preferably made of stiff wire, bent to shape and welded end-to-end. Alternatively, the ends may be bent or twisted together or looped to the handle member.

A further form or frame comprises upper and lower parallel sides connected intermediately of their length (preferably by welding or brazing) by one or more cross-members. In this case, flat strip is preferably used, with the width of the strip in the plane of the frame, to impart the necessary rigidity. The upper side of the frame is adapted to clip under the lateral projections of the handle pressure member and the lower side

2

may be supported from the internal tension member by a connector bar of known type which also supports the upper edge of the lower plate and the lower edge of the upper plate.

The frame may be provided with inwardly projecting prongs adapted to be disposed one at either side of the tension member to prevent sideways displacement of the frame. The prongs also serve to bear against the connector bar to restrain the latter against displacement from its normal operative position.

If two or more tension members are used in the cloche then two or more sets of prongs may be provided on the frame.

15 A frame may be disposed at each side of the cloche, thus permitting removal of two upper plates.

The frame or frames impart rigidity to and preserve the symmetry of the whole structure, especially when the cloche is turned on its end for storage or for certain horticultural purposes.

20 The handle pressure member for use with the support frame preferably comprises a length of wire coiled into a loop forming the handle proper, the ends of the wire extending in opposite directions from the handle loop and each terminating in a long loop commencing in a plane substantially normal to the plane of the handle loop and then bending upwards out of the plane. The free extremities of the wire may form extensions at the opposite sides of the main length of the wire to the long loop for retaining the upper plate or frame at that side, or a small loop may be formed at the opposite side before turning the wire into the long loop. Such a handle facilitates fixing and removal of the upper plate and the frame, and may, moreover, be provided with at least one serration in each long loop and/or extension to hold the upper plate or plates clear of the ridge, the gap thus formed affording ventilation.

25 The invention will be further described with reference to the accompanying drawings in which

30 Figure 1 is a perspective view of a cloche provided with a support frame according to the invention;

35 Figure 2 is an end view of Figure 1;

40 Figure 3 is a scrap view showing release of handle loops for removal of upper plate;

45 Figure 4 is a partial perspective view showing a modified form of support frame;

50 Figure 5 is a partial end view of Figure 4;

55 Figure 6 is a perspective view on reduced scale of the support frame in Figure 4;

Figure 7 is a scrap perspective view showing a modification to the frame of Figures 4, 5 and 6;

Figure 8 is an end view of the cloche incorporating the frame of Figure 7;

Figure 9 is a perspective view of a frame showing an alternative construction of the modification of Figure 7; and

Figures 10, 11 and 12 are scrap views showing alternative formations of the handle and extensions.

In Figures 1 and 2, a cloche of the barn type is shown comprising front and back lower plates 10, 11 and front and back relatively inclined upper plates 12, 13 supported over an internal transverse tension member 14, hooked at 15 under the lower edge of the lower plates, and held in position by a handle 16 forming a pressure member engaging the tension member and bearing on adjacent upper edges of the upper plates 12, 13. The adjacent edges of the two back plates 11, 13 are supported from the internal tension member 14 by a connector bar 17 formed from stiff wire and having serrated ends 18 passing between and engaging the edges of the plates at each side of the tension member, which passes between the plates and the connector bar. The adjacent edges of the two front plates 10, 12 are supported from the tension member by a supporting frame 19, as hereinafter described.

The support frame is made of stiff wire, preferably galvanised, bent to shape and welded end-to-end. It has parallel lower and upper sides 20, 21 connected by end members 22, 23. The lower side 20 is formed with a central inwardly projecting loop 24 through which passes the tension member 14, as shown more clearly in Figure 2, and turns at each end into serrations 25, 26 forming two pairs of aligned serrations, the serrations 25 engaging the lower edge of the upper plate 12 and the serrations 26 the upper edge of the lower plate 10, thus holding these adjacent edges against outward displacement.

The end members of the frame 22, 23 are substantially at right angles to the upper and lower sides and space these latter sides apart by an amount sufficient to bring the upper side approximately into alignment with the under surface of the upper front plate 12. Both the upper edge of the plate 12 and the upper side of the frame clip under lateral extension loops 27 of the handle 15, the upper edge of the back plate 13 clipping under extensions 28 of the handle loops, projecting at the opposite side of the main wire of the handle to the loops 27.

It will thus be clearly seen that when the handle end loops 27 are sprung clear of the upper edge of the plate 12, as shown in Figure 3, and the upper plate removed for purposes previously described, the frame 19 will be held in compression between the handle and the lower plate 10 to retain the rigidity and shape of the structure. Furthermore the upper plate may be readily replaced without disturbing the rigidity of the structure.

The handle as shown in Figures 1, 2 and 3 is formed from a length of wire, preferably galvanised, coiled into a central loop 29, forming the handle proper, the ends of the wire extending in opposite directions from the loop to form two arms 30 each terminating in the long flat loop 27 extending to the front side of the main wire and commencing in a plane substantially normal to the plane of the handle loop, outer ends 31 of the loops 27 being bent upwards out of the plane. The free ends of the handle wire form the extensions 28 at the opposite side of the main wire to the loops 27.

The arms 30 of the handle are each bent downwardly at 32 in the same plane as the handle loop just before turning into the end loops 27 in order to bring the plane of the loops substantially parallel with the upper edges of the upper plates 12, 13 in the operative position of the handle, in which the loops 27 bear down on the upper edge of the plate 13 and the extensions 28 on the upper edge of the plate 12.

10 The central loop 29 acts as a spring, and, in the operative position of the handle as shown in Figures 1 and 2, is held in compression by the tension member 14 which passes through the loop 29. It will thus be seen that the loops 27 and extensions 28 exert a downward pressure on the upward edges of the plates 12, 13 and it will be appreciated that the free shape of the handle will be determined by the magnitude of the pressure required to be exerted.

20 The end 31 of the loop 27 comfortably engages the finger or thumb under the fairly high pressure needed to spring the loop for insertion or removal of the plate 12 or the frame 19.

25 Referring now to Figures 4, 5 and 6, another form of support frame 33 is shown in conjunction with a handle having end loops 34 stepped to form serrations 35 to receive the upper edge of the plate 12 in a raised position for ventilation purposes. The end of the loop 34 is comfortably 30 engaged by the finger and thumb for insertion or removal of the plate 12 or the frame 33, or adjustment of the plate 12 in the serration 35.

35 The frame 33 is formed from flat strip material, preferably galvanised steel, and has parallel upper and lower sides 36, 37 and a cross-member 38 welded, or otherwise connected, at its ends midway along the upper and lower sides thus forming a flat frame of H-shape, with the width of the strip in the plane of the frame to 40 impart the necessary rigidity. The frame used in conjunction with a connector bar 39, similar to the connector bar 17 of Figures 1 and 2, having serrated ends 40 engaging the upper edge of the lower plate 10 in one serration and the lower edges of the frame and upper plate 12 in the other serrations. The connector bar engages the transverse tension member 14 and thus holds the adjacent edges of the plates and the frame against outwards displacement. The upper edge 45 of the frame is approximately in line with the under surface of the upper edge of the plate 12 and both edges clip the lateral loops 34 of the 50 handle.

55 The upper plate 12 may be removed and replaced as previously described with reference to the frame 19, the frame 33 retaining the shape and rigidity of the structure at all times.

56 The handle of Figure 1 may be used with the frame of Figure 4 and vice versa.

60 Figures 7, 8 and 9 illustrate modifications to the frame 33 as shown in Figures 4, 5 and 6. Figure 7 is a scrap perspective view showing a frame assembled in position in relation to the lower plate at one side of the cloche, the handle pressure member and upper plate being omitted for sake of clarity. The cross-member connecting the upper and lower sides 36, 37 of the frame is formed from a stiff round wire 41 bent adjacent the lower side 37 to form an inwardly projecting loop 42, the end of the wire then being looped at 43 in the plane of the frame and the free end bent inwardly at 44 to form, in conjunction with the leg 45 of the loop 42, two prongs disposed one at each side of the internal tension member 14, thus holding the frame against 70 75

sideways displacement. The prongs also are adapted to bear against the connector bar 39, as shown the more clearly in Figure 8, and so restrain the connector bar from rotation about its pivot along the upper edge of the lower plate 10.

The cross member 41 is secured to the upper and lower sides of the frame by welding as shown at 46, 47.

Figure 9 shows an alternative construction of the prongs. A U-shaped wire is welded at 49 to the cross-member 38 of the frame 33, the two limbs of the U forming prongs 49, 50.

Figures 10, 11 and 12 show modifications to the handle end extensions. In Figure 10 a modification of the end loops 34 of Figure 4 is shown, in which the extension of the wire at the opposite side of the handle main wire to the loop 34 is provided with one or more serrations 51 to enable adjustment of the back plate 13 for ventilation. The extension of the end loop 27 of Figure 1 may be similarly formed.

Figure 11 shows the handle wire bent into a small loop 52 before turning into the serrated loop 34 (or similarly the plain loop 27), the loop 52 extending to the opposite side of the handle to the loop 34 (or 27) to engage the upper edge of the back upper plate. The free ends of the wire in this case does not project beyond the main wire or arm of the hands.

The Figure 12 then shows the handle wire formed into the small loop 52 and then bent to form a single serrated wire extension 53 for engagement with the front upper plate and frame, the free end of the wire being formed into a loop 54, which comfortably engages the finger or thumb for springing the extension 53 on insertion or removal of the upper plate or frame.

What we claim is:

1. A barn-shaped cloche comprising a handle forming a pressure member, lateral projections being formed on the handle, an internal transverse tension member engaged by the pressure member, a lengthwise connector bar engaging the tension member, upper and lower transparent plates at a side of the cloche, the connector bar having ends shaped to engage the adjacent edges of the upper and lower plates, with the upper edge of the upper plate engaged compressively by the lateral projections of the handle, a lengthwise supporting member disposed adjacent to the handle and parallel to the connector bar and also engaged compressively by the lateral projections of the handle, and at least one cross-spacing member rigidly secured to the supporting member and extending to the connector bar to transmit compressive thrust from the supporting member to the connector bar.

2. A barn-shaped cloche comprising a handle forming a pressure member, lateral projections being formed on the handle, an internal transverse tension member engaged by the pressure member, a lengthwise connector bar engaging the tension member, upper and lower transparent plates at a side of the cloche, the connector bar having ends shaped to engage the adjacent edges

of the upper and lower plates, with the upper edge of the upper plate engaged compressively by the lateral projections of the handle, a lengthwise supporting member disposed adjacent to the handle and parallel to the connector bar and also engaged compressively by the lateral projections of the handle, and cross-spacing members rigidly secured to the ends of the supporting member and also to the ends of the connector bar, to enable compressive thrust to be transmitted from the supporting member to the connector bar.

3. A barn-shaped cloche comprising a handle forming a pressure member, lateral projections being formed on the handle, an internal transverse tension member engaged by the pressure member, a lengthwise connector bar engaging the tension member, upper and lower transparent plates at a side of the cloche, the connector bar having ends shaped to engage the adjacent edges of the upper and lower plates, with the upper edge of the upper plate engaged compressively by the lateral projections of the handle, a lengthwise supporting member disposed adjacent to the handle and parallel to the connector bar and also engaged compressively by the lateral projections of the handle, a further lengthwise member parallel to the supporting member, at least one cross-spacing member rigidly secured between the supporting member and the further lengthwise member and being of such length that the further lengthwise member engages the shaped ends of the connector bar, to enable compressive thrust to be transmitted from the supporting member to the connector bar.

4. A cloche as in claim 3, wherein a single cross-spacing member is provided, rigidly secured at its ends to the centers of the supporting member and further lengthwise member respectively, and downwardly extending prongs being provided near the lower end of the cross-spacing member to embrace the tension member to secure the further lengthwise member and the supporting member against lengthwise displacement.

5. A cloche as in claim 4, comprising downwardly bent portions of the lower end of the cross-spacing member itself to provide the prongs.

HENRY THOMAS LLOYD LOFTUS-
TOTENHAM.
